LAMP HOLDER

Frank C. De Reamer, Bridgeport, and Adolf G. Mueller, Stratford, Conn., assignors to General Electric Company, a corporation of New York

Application May 17, 1939, Serial No. 274,202

5 Claims. (Cl. 173—328)

This invention relates to lampholders, and more particularly to lampholders for tubular lamps of the type having spaced contact pins for engagement with the lampholder.

An object of the invention is the provision of an improved lampholder of the type described which insures positive contact with the lamp contact pins, which will support the lamp in any position and which is formed of relatively few parts such that it may be manufactured at low cost.

In the accompanying drawing, Fig. 1 is a perspective view of a pair of lampholders, together with a tubular lamp showing the manner in which the lamp is mounted in the lampholder; Fig. 2 is an exploded view of the elements of the lampholder; Fig. 3 is a rear view of the lampholder with a closure plate removed showing the interior thereof; Fig. 4 is a front view of the lampholder showing the position of the lamp contact pins in mounted position; and Fig. 5 is a sectional view through the lampholder along the line 5—5 of Fig. 3.

Referring to Fig. 1 of the drawing, a plurality of lampholders 10 are shown in spaced relationship for supporting the ends of a tubular lamp 11, for example, a fluorescent lamp. The ends of the lamp are provided with spaced contact pins 12 which cooperate with the contact means of the lampholder in a manner to be described later.

The lampholder 10 includes a base member 13 of insulating material which is provided with a recess 14 extending from the inner face 15 thereof. At its outer face 16 the base member is provided with two parallel slots 17 which merge with the recess 14 and which are adapted to receive the lamp contact pins 12. The slots are separated one from the other by a distance corresponding to the spacing of the contact pins of the lamp. A boss 18 extends from the bottom of the recess 14 and divides it into two compartments 19 and 20 for receiving the lampholder contact means. At one end the walls of the boss form flat bearing surfaces 21 and 22 merging with the walls of the slots 17, while at the other end the walls of the boss are beveled toward each other, as shown at 23, to form an extension 24. The outer walls of the compartments 19 and 20 are provided with grooves 25 while each side of the extension 24 is provided with a flange or bead 26 which cooperates with the groove 25 in providing a support for the contact means of the lampholder.

The contact means includes flexible spring con-

tact blades 27. As shown most clearly by Figs. 2 and 3, one end 28 of each of the contact blades is bent at an angle and is spot welded, or otherwise secured, to the top of a terminal plate 29. The terminal plates and bent ends of the contact members are then seated in the pockets formed by the grooves 25 and beads 26. A shelf 30 extends from the bottom of the recess in each of the compartments and engages the top of the bent end of the contact blade to assist in holding it in position. The main portion of the contact blade 27 extends upwardly at an angle to the terminal plate 29 within its corresponding compartment in the recess 14. A contact blade and terminal plate assembly are mounted on each side of the boss 18. The upper end of each contact blade is given an S-shaped configuration to form a pocket 31 and a beveled surface 32 which are in alignment with the corresponding slot 17, so that as the lamp contact pins are pressed into the slots they will engage the contact blades. A terminal screw 33 is threaded into each of the terminal plates 29.

Upon insertion of the lamp contact pins in the grooves, the pins engage the beveled or sloping bearing surface 32 and flex the flexible spring contact blades outwardly permitting the pins to drop into the depressions 31 in which position they are locked in engagement with the lampholder, as shown by Fig. 4. The pins are seated in the depressions 31 and are biased by the spring action of the contact blades into engagement with the walls 21 and 22 of the boss 18 as well as the walls of the slots 17. This means that the contact pins are firmly held within the lampholder making it possible to mount the tubular lamp in any position, even by suspending it from the ceiling, because considerable force is necessary to remove the lamp by springing the ends of the contact blades outwardly. The slots 17 serve to guide the contact pins into engagement with the contacts and prevent any binding or twisting of the contact pins such as might damage the lamp.

As already described, the dividing boss 18 is tapered inwardly at each side to form the extension 24. Accordingly, each of the contact blades may be bent at an angle of approximately 30 degrees to the vertical parallel with the beveled portions of the dividing boss so that the bent terminal portions of the contact blades and the terminal plates are in substantial vertical alignment with the guide slots 17. This means that at one end the contact blades are spaced apart a distance corresponding to the spacing between

the lamp contact pins 12, while at the other end they are spaced apart a relatively small distance corresponding to the thickness of the extension 24. By this construction the overall dimensions of the lampholder are greatly reduced since it is unnecessary to space the contact terminal means a distance corresponding to the spacing of the slots 17. In addition, the angular or oblique arrangement of the contact blades make room for the ends of the terminal screws 33 within the compartments 19 and 20 above the bent ends 28 of the contact blades whenever the screws are threaded up into the terminal plates. This arrangement is shown by Fig. 3.

By mounting the flexible spring contact blades upon the relatively heavy terminal plates a rugged construction of the contact means is attained and one which will hold the lamp contact pins securely within the lampholder. The terminal plates provide an adequate support for the terminal screws, so that there is no chance of damaging the contact means upon threading down the terminal screws in connecting a conductor. The extension 24 projects downwardly below the level of the heads of the terminal screws 33 and serves to insulate the attached conductors from each other. Since each of the contact blades and terminal plates are identical in construction, the number of parts is reduced and they may be easily assembled together. The assembly may then be mounted in the body of the lampholder simply by slipping the terminal plates and contact blades within the grooves 25 and compartments 19 and 20. In assembled position the contact blades are flexed slightly and biased into engagement with the upper portions of the boss 18, so that the lamp prong engaging portions of the contact blades are always in correct position adjacent the slots 17.

The contact means are held in position by a cover plate 34 of insulating material, for example, sheet fiber. The cover plate is secured to the base member by a plurality of drive pins 35 which pass through openings 36 and 37 formed in the cover plate and base member, respectively. In the lower portion of the cover plate spaced recesses 38 are provided which are in alignment with the terminal screws 33 to permit passage of the conductors to be secured to the terminal screws. Similarly, the base member 13 is provided with spaced recesses 39 in its lower edge for receiving the conductors. The cover plate rests upon a notched edge 15' of the rear face of the base member 13 and is also flush against the face of the boss 18 and the edges of the contact blades and terminal members. In this manner the contact blades are held securely in position and since the cover plate is countersunk in the edge 15', the rear face 15 of the base and cover plate are flush with each other giving the assembly a pleasing appearance, as shown by Fig. 1.

In order to provide a mounting means for the lampholder, a plurality of ears 40 are formed on opposite sides of the base member 13. Each ear is provided with a recess 41 merging with a slot 42 with the latter extending through the ear for receiving a mounting bolt 43, as shown by Fig. 5. A nut 44 rests within the recess 41 and engages the end of the bolt for mounting the lampholder upon a support. In mounting the lampholder it is necessary only to place the nut 44 in the recess 41 and thread the bolt 43 into the nut; the walls of the recess 41 cooperate with the nut

5 to prevent rotation thereof. While this structure provides an effective and simple means of mounting the lampholder on a support, it should be manifest that other mounting means may be employed as occasion demands.

In mounting a tubular lamp, two lampholders are employed, one to support each end of the lamp, and the lampholders are spaced apart a distance depending upon the length of the lamp. 10 The lamp is mounted simply by placing the contact pins in the slots 17 and pressing downwardly on the lamp until the pins engage the contact means in the manner described. Several of the lamps may be mounted in line by placing the lampholders back-to-back. In most cases the lampholders are surface mounted directly upon the upper surface of a support. However, if it is desired to conceal the wiring the support may be provided with slots through which the base member 13 extends for supporting the lamp on the top of the support while the ears 40 remain beneath the support and the conductors are connected to the terminal screws underneath the support where they are out of sight.

What we claim as new and desire to secure by Letters Patent of the United States is:

1. A socket for electric lamps having contact prongs comprising a base of insulating material having a recess therein extending from one face thereof, spaced parallel slots extending from the opposite face thereof to an edge of said last mentioned face and merging with said recess, spaced contact members in said recess, one end of each contact member having a lamp prong engaging portion resting in a corresponding slot, the walls of said recess being provided with grooves therein, terminal plates in said recess, the other end of each of said contact members being bent at an angle and welded to a corresponding terminal plate, said bent ends of said contacts and said terminal plates being seated in said grooves, and conductor fastening means mounted on each of said plates.

2. A socket for electric lamps having contact prongs comprising a base of insulating material having a recess therein extending from one face thereof, spaced parallel slots extending from the opposite face thereof to an edge of said last mentioned face and merging with said recess, spaced contact members in said recess, one end of each contact member having a lamp prong engaging portion resting in a corresponding slot, the walls of said recess being provided with grooves therein, terminal plates in said recess, the other end of each of said contact members being bent at an angle and welded to a corresponding terminal plate, said bent ends of said contacts and said terminal plates being seated in said grooves, conductor fastening means mounted on each of said plates, and a closure plate covering said recess and holding said contact members and terminal plates in position.

3. In a lamp socket for use with a lamp having spaced contact prongs, a base member having a recess therein and spaced parallel elongated slots merging with said recess, a boss extending from the bottom of said recess between said slots and dividing said recess into two compartments, a flexible spring contact blade in each compartment, a terminal plate in each compartment and a conductor fastening means mounted on each of said plates, one end of each contact blade being secured to said terminal plate, the other end of each contact blade resting in a corresponding slot for engagement by a lamp prong,

each of said contact blades being bent at an angle whereby said terminal plates and fastening means are in substantially vertical alignment with said parallel slots.

4. In a lamp socket, a base having a recess therein, a boss having a tapered extension dividing said recess into two compartments, spaced parallel slots in said base member, one slot merging with each compartment, a flexible spring contact blade in each compartment, one end of each blade extending within said slot for engagement with a lamp contact, a terminal plate in each compartment, the other end of each contact blade being bent at an angle and secured to a corresponding terminal plate, grooves in the walls of said compartments for supporting said terminal plates, terminal screws mounted on said plates, said contact blades being extended angularly toward each other in a direction substantially parallel to said tapered extension whereby said terminal plates are in substantially vertical align-

ment with the lamp contact engaging portions of said contact blades.

5. A socket for electric lamps having spaced contact prongs comprising, a base of insulating material having a recess therein extending from one face thereof, spaced parallel slots extending from the opposite face thereof to the edge of said last-mentioned face and merging with said recess, spaced contact members in said recess, one end of each contact member having a lamp prong engaging portion resting in a corresponding slot, the walls of said recess being provided with grooves therein, terminal plates in said recess, the other end of each of said contact members being bent at an angle and fastened to a corresponding terminal plate, said terminal plates being seated in said grooves and conductor fastening means mounted on each of said plates.
